PORTABLE REFRIGERATOR

Morris Brodheim, Philadelphia, Pa.

Application January 4, 1952, Serial No. 264,940

1 Claim. (Cl. 62—116)

This invention relates to refrigerators, and more particularly to a portable electrically operated refrigerator.

The main object of the invention is to provide a novel and improved portable electric refrigerator which is simple in construction, which is compact in size, and which is light in weight.

A further object of the invention is to provide an improved portable electric refrigerator which may be easily transported from place to place, which utilizes the food storage space therein in a very efficient manner, which is inexpensive to manufacture, and which is entirely self-contained.

A still further object of the invention is to provide an improved portable electrical refrigerator which is of relatively small bulk, which provides convenient access directly to all the food storage compartments thereof, and which employs inexpensive and readily available components.

Further objects and advantages of the invention will become apparent from the following description and claim, and from the accompanying drawings, wherein:

Figure 1 is a front elevational view of an improved portable electric refrigerator constructed in accordance with the present invention.

Figure 2 is an end elevational view of the portable electric refrigerator of Figure 1.

Figure 3 is a top view of the portable refrigerator of Figures 1 and 2 with the top and front covers in open positions.

Figure 4 is a longitudinal vertical cross sectional view taken on the line 4—4 of Figure 2.

Figure 5 is a transverse vertical cross sectional view taken on the line 5—5 of Figure 3.

Figure 6 is a vertical transverse cross sectional view taken on the line 6—6 of Figure 1.

Figure 7 is a schematic view showing the electrical wiring connections and the conduit connections of the elements of the refrigerating mechanism employed in the portable refrigerator of Figures 1 to 6.

Referring to the drawings, the refrigerator is designated generally at 11 and comprises a generally rectangular housing 12 having front and rear walls 13 and 14, end walls 15 and 16, a bottom wall 17, and a top wall 18 which is hinged at 19 to the rear longitudinal top corner of the rear wall 14 so that the wall 18 defines a hinged top cover. The walls and top cover are suitably insulated to minimize heat flow therethrough, and may include suitable heat insulating material such as cork, mineral wool, or other well known insulating material.

Designated at 20 is a transverse vertical partition wall provided in the housing 13 defining a food compartment 21 on one side thereof and a compressor compartment 22 on the other side thereof. As shown in Figure 3, the compressor compartment 22 is defined between end wall 15 and partition wall 20, and the food compartment 21 is defined between end wall 16 and partition wall 20.

The food compartment 21 is provided at front wall 13 with a hinged cover 23 communicating with the lower

portion of the food compartment 21. The cover 23 is provided with a latch 24 of the type which locks when the cover is moved into closed position and which may be opened by rotating the latch handle, shown at 25. Mounted in the opening receiving the cover 23 is a lamp bulb 26 which is connected in series with the door-operated switch, of conventional construction, as shown at 27, to the line wires 28 and 29, as shown in Figure 7. The line wires 28 and 29 form part of a conventional line cord extending from the refrigerator and adapted to be plugged into a convenient electric socket at the location where the refrigerator is to be used. As in the case of a conventional refrigerator, when the door 23 is opened, the switch 27 closes energizing the lamp 26 and illuminating the interior of the food compartment of the refrigerator.

Designated at 29 is the evaporator compartment which contains the refrigerator evaporator coils and which is provided with shelves for receiving trays 30 for making ice cubes. The evaporator unit 29 is mounted on the upper portion of the partition wall 20 against the upper portion of rear wall 14, as shown in Figures 3 and 4. Evaporator unit 29 is rigidly secured to walls 14 and 20 and is of conventional construction. Mounted on a bracket 31 secured to the partition wall 20 under the evaporator unit 29 is a removable defrost tray 32 which is employed for the collection of moisture dripping from the evaporator unit 29 when the refrigerator is defrosted.

Designated at 33 is a horizontal food supporting tray 33 which is removably mounted on inwardly projecting lugs 34 provided on the inside surfaces of the walls 16 and 14 and on the evaporator unit 29, said lugs 34 being arranged to support the food tray 33 in a horizontal position. The food tray 33 is shaped to cover substantially the entire horizontal cross sectional area of the food compartment 21 and is formed to fit around the evaporator unit 29, as illustrated.

Secured to the end wall 16 in the lower portion of the food compartment 21 is a clamping bracket 35 provided with opposed resilient arcuate clamping fingers 36, 36 arranged to clampingly receive the neck of a milk bottle 37 therebetween, as shown in Figures 4 and 5. It will be further apparent from Figure 3 that when the door 23 is opened, convenient access is provided to the milk bottle, said bottle being located adjacent the door opening. Access is provided to the upper portion of the food compartment, namely, the food supported on the tray 33 by opening the hinged top wall 18. Access to the freezer trays 30 is similar provided by opening either the door 23 or the hinged top cover 18. For convenience in reaching the lower freezer tray 30, the door 23 may be employed, and similarly, to reach the upper tray 30, the hinged top cover 18 may be opened.

Mounted in the compressor compartment 22 are the components of a conventional mechanical refrigeration system including the compressor 35, the accumulator 36, the drier 37 and the blower fan 38. Mounted in the rear wall 14 is the condenser 39', the blower fan 38 being arranged to blow air through the condenser 39' to cool the refrigerant, in the well known manner. Also mounted in the compressor compartment 22 is a thermostat control device 39 comprising a thermostatically operated switch connected in series between the motor of the compressor 35 and the line wires 28 and 29 and provided with conventional means for adjusting the temperature at which the switch contacts thereof close. The operating means for the thermostat includes a conventional bulb device 40 located adjacent the evaporator unit 29 and connected by a conduit 41 to the thermostat switch unit 39 so as to operate the contacts thereof. As shown in Figure 7, the evaporator is connected to the condenser 39' by the capillary refrigerant flow control line 42, the condenser 39'

being in turn connected by the conduit 43 to the low pressure side of the compressor 35. The high pressure port of the compressor is connected by a conduit 44 through the drier 37, the conduit 45 and the accumulator 36 to the evaporator unit 29, thereby completing the refrigeration circuit. The blower motor 38 is connected in parallel with the line wires 28 and 29 by the respective wires 46 and 47, as shown in Figure 7. When the line wires 28 and 29 are connected to an electric socket, the compressor 35 becomes energized and continues to operate until its circuit is opened by the opening of the contacts of the thermostat unit 39, namely, when the desired temperature of the evaporator unit 29 has been reached, in accordance with the setting of the thermostat unit. The blower motor 38 is, of course, energized and blows air through the condenser 39, cooling the expanded refrigerant prior to the return of the refrigerant to the compressor 35, as in the usual refrigeration cycle.

As shown in Figure 4, the end wall 15 is provided with the louvered opening 47 so that air may flow through the compressor compartment 22 to cool the condenser 39. The front wall 13 of the housing 12 is also formed with a louvered opening 48 communicating with the compressor compartment 22 to increase the circulation of air through the compressor compartment 22.

Secured to the upper intermediate portions of the end walls 15 and 16 are the respective handles 49, 49, enabling the refrigerator to be readily lifted and carried.

While a specific embodiment of an improved portable electric refrigerator has been disclosed in the foregoing description, it will be understood that various modifications within the spirit of the invention may occur to those skilled in the art. Therefore, it is intended that no limitations be placed on the invention except as defined by the scope of the appended claim.

35

What is claimed is:

In a portable refrigerator, a rectangular housing having an open top, a bottom wall, a front wall, a rear wall, and end walls, a cover hinged on the housing and closing the open top thereof, a vertical transverse partition wall in said housing extending the full width and height of the interior of the housing and dividing the interior of the housing into a food compartment and a compressor compartment, an evaporator assembly secured to upper portions of said partition wall and said rear wall and spaced from said bottom wall and from the adjacent end wall, a food tray spaced upwardly from said bottom wall and extending between said front and rear walls and between said adjacent end wall and said evaporator assembly, means supporting said food tray on said front and rear walls and on said adjacent end wall and said evaporator assembly, said front wall having an opening providing access to the food compartment, and a door hinged on said housing and closing said access opening, a compressor assembly in said compressor compartment, said rear wall having a condenser opening into the compressor compartment, and a condenser mounted within said condenser opening and connected to the compressor assembly.
